[57] CLAIM

The ornamental design for an envelope, as shown.

DESCRIPTION

FIG. 1 is a top perspective view of an envelope showing my new design;
FIG. 2 is a top elevational view thereof;
FIG. 3 is a bottom elevational view thereof;
FIG. 4 is a right side elevational view thereof;
FIG. 5 is a left side elevational view thereof;
FIG. 6 is a bottom plan view thereof;
FIG. 7 is a top perspective view of a second embodiment of the envelope shown in FIG. 1 wherein the broken lines represent conventional stitching;
FIG. 8 is a top elevational view thereof;
FIG. 9 is a bottom elevational view thereof;
FIG. 10 is a right side elevational view thereof;
FIG. 11 is a left side elevational view thereof; and
FIG. 12 is a bottom plan view thereof.

*FIG. 1**FIG. 5**FIG. 2****FIG. 7******FIG. 8***
